UNITED STATES PATENT OFFICE.

WILLIAM D. GEROW AND FRANKLIN O. PRUSIA, OF DETROIT, MICHIGAN.

METALLIC VEHICLE-BODY.

1,271,697.

Specification of Letters Patent. Patented July 9, 1918.

Application filed December 2, 1916. Serial No. 134,569.

To all whom it may concern:

Be it known that we, WILLIAM D. GEROW and FRANKLIN O. PRUSIA, both citizens of the United States of America, residing at 5 Detroit, in the county of Wayne and State of Michigan, have invented certain new and useful Improvements in Metallic Vehicle-Bodies, of which the following is a specification, reference being had therein to the accompanying drawings.

The invention relates to metallic bodies for vehicles and has particular reference to the construction of a metallic frame for supporting the metal sheets. It is the object of 15 the invention to obtain a construction of frame which may be readily fashioned as desired and which is adapted to be easily secured to the sheet-metal panels, affording a stable support therefor.

20 In the drawings:

Figure 1 is a side elevation of a metallic vehicle body embodying our invention;

Fig. 2 is a plan view thereof;

Fig. 3 is a plan view of a portion of the 25 supporting base frame;

Fig. 4 is a perspective view of a portion of the sill;

Fig. 5 is a section on line α — α Fig. 1.

Broadly described, our invention comprises the use of fashioned ribs of channel-shaped cross-section assembled to constitute the frame and having the channels arranged so that the sides thereof lie adjacent to the inner and outer sheet-metal panels. In detail, the base or sill of the frame is composed of a longitudinal channel strip A fashioned to the desired contour and bent to extend around the entire frame. This strip is braced by transverse braces B also formed of channel bars. Struts D are preferably arranged between the sides of the channel at frequent intervals, these being formed of U-shaped members spot-welded or otherwise secured in position.

45 Upon the base frame or sill are mounted the post sections E also formed of channel strips pressed to the desired contour. At the top the posts are connected by a fashioned frame bar F also formed of channel 50 strips. All of these parts may be readily united to each other by overlapping the sides of the adjacent channel bars and spot-welding or otherwise securing the same to each other. The same construction may be used 55 in forming the door frames, as indicated at G, and seat frames, as indicated at H. Di-

agonal braces I may be arranged wherever necessary to impart the desired degree of strength.

Upon the frame constructed as described, 60 the pressed sheets forming the panels of the body are laid and are attached, preferably by spot-welding at frequent intervals to the adjacent flanges of the bars.

A body constructed as above described has 65 the advantage of being entirely metallic and at the same time the various elements of the frame make it easily fashioned and quickly assembled. It therefore has an obvious advantage over constructions employing wooden 70 frames for supporting the metallic sheets.

To conform to the contour of the body the web portion A' of the channel bar A, which forms the sill, may be inclined as shown, and to support the floor boards the lower flange 75 A² may be extended beyond the upper flange so as to produce a supporting ledge for the ends of said floor boards J. Thus the ends of the boards may abut against the upper 80 ends of the channel while the lower flange will afford the necessary support.

What we claim as our invention is:

1. In a metallic body for vehicles, a frame comprising fashioned metallic bars of channel cross section arranged with the sides 85 of the channel conforming to the curvature of the metallic sheets to be secured thereto.

2. In a metallic body for vehicles, a frame comprising fashioned metallic bars of channel cross section, the sides of the channels 90 conforming to the curvature of the sheets to be attached thereto, said bars being secured to each other by overlapping the flanges thereof.

3. In a metallic body for vehicles, a frame 95 formed of curved metallic bars of channel cross section, said bars intersecting and overlapping each other, the overlapping portions being spot-welded, and sheet-metal panels overlying said frame and welded to 100 the sides of the bars thereof.

4. In a metallic body for vehicles, a frame formed of fashioned curved bars of channel cross section, the sides of said bars being arranged parallel to the body sheets and the 105 joint between adjacent bars being formed by overlapping sides secured to each other, and body sheets overlying said bars and welded thereto.

5. In a metallic body for vehicles, a frame 110 comprising a sill formed of channel cross section, with the parallel flanges thereof ar-

- ranged in horizontal planes, brace-bars extending between different portions of the sill, curved posts extending upward from the sill, and a curved border frame secured 5 to the upper ends of said posts, all of said members being formed of metallic channel bars secured to each other by overlapping portions of the flanges thereof.
6. In a metallic body for vehicles, a supporting frame formed of metallic channel bars and comprising a sill bar, upwardly-extending posts and a top border frame, the flanges of the sill being arranged in horizontal planes and the flanges of the posts 15 and top frame conforming to the curvature of the body sheets.
7. In a metallic body for vehicles, a supporting frame, comprising a sill formed of a metallic channel bar, the parallel flanges 20 of which lie in horizontal planes, the web portion of said bar being inclined to conform to the contour of the body and the
- lower flange projecting beyond the edge of the upper flange and a floor board resting upon said lower flange and abutting against 25 said upper flange.
8. In a metallic body for vehicles, fashioned upwardly-extending posts and a fashioned top border frame formed of metallic channel bars, the sides of said bars conforming to the surfaces of the inner and outer body sheets to be secured thereto.
9. In a metallic body for vehicles, the combination with a fashioned frame, of inner and outer curved sheets to be secured 30 thereto, said frame comprising fashioned metallic bars of channel cross section arrangement intermediate said sheets with the sides of the channels conforming to the curvature of the sheets.

In testimony whereof we affix our signatures.

WILLIAM D. GEROW.
FRANKLIN O. PRUSIA.
